UNITED STATES PATENT OFFICE

2,493,481

INTERNAL-COMBUSTION ENGINE

William V. Falcon, Revere, Mass.

Application January 2, 1947, Serial No. 719,860

1 Claim. (Cl. 123—32)

1 My present invention relates to internal combustion engines of the type in which fuel is injected directly into the combustion cylinder by a fuel pump or fuel injection valve. The invention may be embodied either in internal combustion engines of the compression ignition type in which the fuel is ignited by the compression alone or by a timed electric spark. The invention is particularly intended to improve the combustion so that the injected fuel will be more completely and uniformly burned; there will be less residue of unburned fuel to cause crank case dilution, and the speed of vaporization of the fuel and combustion of the mixture will be increased, making possible higher engine speeds.

These results are accomplished in part by drawing the heated air directly from the top of the combustion chamber and mixing it with the fuel before and as it enters the combustion chamber. Since the air from the combustion chamber is hot from the previous explosion at the time when it is mixed with the fuel, the fuel is more completely and more rapidly vaporized when it enters the combustion chamber and, therefore, the lighter and more combustible portion tends to rise to the top of the chamber toward the point where ignition begins, whether caused by compression or by a timed electric spark. Also the provision of heat at the time when the fuel is vaporized tends to increase the amount of fuel which is vaporized and reduce the size of unvaporized particles and consequently the amount of liquid fuel remaining after the explosion and thus reducing crank case dilution.

In the drawings:

Fig. 1 is a sectional elevation of a compression ignition engine, embodying my invention.

Fig. 2 is a similar section of the essential parts of an engine adapted to be operated by a timed electric ignition and embodying my invention in modified form.

Fig. 3 is a section on line 3—3 of Fig. 1 looking downward.

Fig. 4 is a similar section on 4—4 of Fig. 2.

Referring now to Fig. 1 of the drawings, at 1 is shown a conventional cylinder block containing a cylinder 2. At 3 is shown the cylinder head having a combustion space 4 which is located over one part only of the cylinder and is, in general, circular and dome-shaped. Located in the side wall of the cylinder head is a restricted passage 6 by which the combustion space 4 communicates with a vertical restricted passage 7, the upper end of which is closed by a screw 8 and the lower end of which leads to an

12 annular space 9 formed between the spray nozzle 10 and the jet 11. The spray nozzle 10 is a separate piece screwed into the wall of the cylinder head and has a central passage 12 which is somewhat tapering toward the outlet. The jet 11 is screwed into the valve body 13 containing the injection valve 14, leaving the annular space 9 between the jet 11 and the spray nozzle 10. The valve mechanism shown is of novel construction and forms part of a companion application filed herewith. Accordingly, as it forms no part of the present invention, it will not be described in detail herein.

2 Fuel is injected under high pressure through the jet 11 into the spray nozzle 10. When the injected fuel leaves the tip of the jet 11 it is travelling at high velocity and carries air from the annular space 9 with it into the combustion space 4, thus lowering the pressure in the passage 7 and drawing hot air from the top of the combustion space 4 through the opening 6. This produces circular movement of air from the top of the combustion space through the passage 7 and out of the spray nozzle 10 into the combustion space. Since the air in the combustion space is highly heated, the heat which is necessary to vaporize the fuel is supplied more rapidly than it would be if the air were cold and therefore tends to reduce the size of the fuel particles. 20 The vapor thus formed and the lighter particles of fuel tend to be drawn upwardly by the circulation while the heavier particles remain at a lower level. Therefore, as the piston rises and the pressure in the cylinder passes the ignition point, 25 ignition takes place first in the portion of the mixture at the top where it approaches most nearly to the condition of a perfect gas. This nucleus of flame spreads rapidly through the entire mass of fuel and air and results in burning 30 the fuel more rapidly and completely than would otherwise be the case.

Referring now to Fig. 2, I have shown therein my present invention applied to an engine employing a timed electric spark ignition with fuel pump injection. The cylinder block is shown at 21, a cylinder at 22 and the cylinder head at 23. At 24 is shown a spray nozzle and at 25 a fuel jet controlled by a fuel valve 26 there being an annular space 34 between the two parts. The combustion space 27 is over a part only of the cylinder and is circular in plan view but is somewhat flattened on the top (see Figs. 2 and 4). At 28 is shown a supplemental combustion space communicating with the combustion chamber 27 by 35 a passage 29 in a thimble 30. At 31 is shown a

screw threaded thimble to receive a spark plug not shown. Leading from the supplemental combustion chamber 28 is a restricted passage 32 connecting with a vertical restricted passage 33 which leads to the annular space 34 between a valve body 35 and the spray nozzle 24. The injection valve is of a different type from that shown in Fig. 1 but since it forms no part of my invention, it is not described in detail.

This engine embodying my invention operates in substantially the same manner as the one previously described. In this case hot air from the combustion space 27 is drawn into the supplemental combustion space 28 and is thence drawn through the passages 32 and 33 into the annular space 34 and mixed with the fuel as it is projected at high velocity out of the fuel jet 25 and through the spray nozzle 24. As previously described the vaporized fuel is projected into and mixed with hot air from the combustion space, and this more highly vaporized fuel tends to be drawn upward into the supplemental combustion chamber so that the spark is introduced into the portion of the charge which is most inflammable.

The construction shown in Fig. 2 is particularly advantageous because it not only has the advantages resulting from mixing hot air with the spray of fuel from the jet, but also because the spark plug is completely protected from contact with any unvaporized particles of fuel. Heretofore, one of the chief difficulties with pump injection engines employing timed electric ignition has been that particles of unburned fuel are projected onto the electrodes of the spark plug which immediately becomes fouled and either less effective or inoperative. Likewise since the vaporization and combustion of the fuel is much improved crank case dilution, which has been the cause of serious trouble with engines of this type, is greatly reduced.

Since the engine embodying my invention reduces the time required for the vaporization and combustion of the fuel and air mixture, it is particularly adapted to use in high speed engines.

I claim:

In an internal combustion engine, a cylinder block containing a piston, a cylinder head having a combustion chamber, a fuel injection valve and a cooperating fuel and air nozzle in one of said parts, said valve and nozzle having an annular space between them, said nozzle opening into one side of said combustion chamber near its bottom in a direction at right angles to the axis of said piston and in close proximity to the top of said piston in the upper position of the latter, said cylinder head being provided with a restricted passage externally of said combustion space and leading from the top of said combustion space at a point remote from said piston in any position of the latter, and to the said annular space between the said valve and nozzle whereby heated air is drawn from the top of the combustion space through the restricted passage and annular space between the jet and nozzle and out through the nozzle and into the lower part of the combustion chamber by fuel injected from the valve through the nozzle, said air being mixed with the fuel as the fuel and air pass through the said annular space and said nozzle, and the finer particles of said fuel and air mixture tending to rise to the top of said combustion chamber.

WILLIAM V. FALCON.
